UNITED STATES PATENT OFFICE

2,475,090

GUN RECOIL MECHANISM

Samuel G. Green, Alexandria, Va., and Walter H. D'Ardenne, Jenkintown Manor, William J. Meinel, Huntingdon Valley, and Weber Devore, Horsham Township, Montgomery County, Pa., assignors, by direct and mesne assignments, to Heintz Manufacturing Company, Philadelphia, Pa., a corporation of Pennsylvania

Original application December 31, 1943, Serial No. 516,520. Divided and this application May 23, 1946, Serial No. 671,874

4 Claims. (Cl. 89—44)

1

This application is a division of copending application, Serial No. 516,520, filed December 31, 1943, which issued on July 30, 1946, as Patent No. 2,404,958.

This invention relates to gun recoil devices and more particularly to a recoil mechanism for machine guns.

An object of the invention is to provide an improved recoil mechanism of the type referred to above.

Another object of the invention is to provide an improved recoil mechanism which is light in weight, simple to manufacture in large scale production, and easy to assemble and disassemble.

These and other objects of the invention will be apparent from the following specification and the accompanying drawings, in which:

Figure 1 is a side elevational view of a machine gun mount employing an improved recoil mechanism;

Figure 2 is a top plan view of the cradle assembly of the mount shown in Figure 1;

Figure 3 is a side elevational view of the cradle assembly;

Figure 4 is a side elevational view of the cradle assembly taken on the opposite side to Figure 3;

Figure 5 is a rear end elevational view of the cradle assembly;

Figure 6 is a detail plan view of the recoil mechanism;

Figure 7 is a detail side elevational view of the recoil mechanism;

Figure 8 is a detail front end view of the recoil mechanism; and

Figure 9 is a longitudinal sectional view taken on line 9—9 of Figure 6.

In the preferred embodiment of the invention shown in the drawings, the novel recoil mechanism is used with a mount which includes a vertical pedestal support or stand 1 adapted to support detachable legs 2 forming a tripod support. A trunnion bracket 3 is detachably secured to the upper end of the stand 1. The upper portion of the stand 1 is mounted for rotary movement about the vertical axis of the stand so that trunnion bracket 3 is capable of movement in a horizontal plane over 360°.

The upper end of the trunnion bracket 3 supports the cradle assembly 4 for pivoting movement in a vertical plane. The cradle assembly

2

is adapted to carry a gun, such as a cal. .50 Browning water-cooled machine gun 5 (shown in broken lines). The cradle assembly 4 and gun may be elevated from minus 15° to plus 90°.

5 The cradle assembly 4 further includes a trigger frame, indicated generally by the reference numeral 6, a trigger side plate mechanism 7 adapted to be secured to the side of the gun 5, a recoil mechanism to be described in detail presently, and a spent ammunition link chute 9. 10 The cradle assembly 4 is adapted to detachably receive an ammunition chest 10 (shown in broken lines).

The trunnion bracket 3, at its base, is provided 15 with means for detachably receiving a shield support 11 carrying an armor plate shield 12 at its upper end.

The cradle assembly 4 is comprised generally 20 of two parallel spaced plates 71, 72 bolted to blocks 73 and 74 so that the blocks serve as spacing means for the plates. The blocks 73, 74 are each provided with a pair of bores in which the ends of the parallel rods 88, 89 are mounted for longitudinal sliding movement. The pairs of 25 bores are provided with suitable bearings to facilitate such sliding movement. The blocks 73, 74, are provided with threaded openings such as 90 in their side faces to permit the cradle plates 71, 72 to be bolted thereto.

30 Adjacent the forward block 73 and mounted rigidly on the rods 88, 89 is a bracket 91 having two upstanding arms 92, 92' provided with aligned transverse openings 93 to receive a removable pin 94 which is adapted to pass through an opening in the gun so as to secure the gun to the recoil mechanism.

35 Another bracket 95 is mounted rigidly on the rods 88, 89 near the block 74 and this bracket has arms 96, 96' provided with aligned openings 97 to receive a pin 98 adapted to pass through another portion of the gun.

The bracket 95 is provided with a central opening adapted to receive a rod 99 which passes therethrough. The rod 99 also passes through 45 an opening in the block 74. Collars 100, 100' are secured at each end of the rod 99 and a coil spring 101 surrounds the rod 99. This spring bears at one end against the bracket 95 and at the other end against the block 74. A second coil spring 50 102 of less tensional strength than spring 101

also surrounding the rod 99 bears at one end against the collar 100 and at the other against the inner wall 103 of a countersunk bore 104 in the block 74 which bore is coaxial with the opening through which the rod 99 passes.

Machine guns of the type used in this mount are provided with their own interior recoil devices but any excess recoil or rebound movements in either a forward or backward direction are absorbed by the two-way recoil mechanism described. It will be seen that since the gun is secured at two points to the brackets 91 and 95, respectively, any recoil movement transmitted to the brackets and rods 88, 89 will be absorbed by the spring 101 while rebound movement in the other direction will be taken up by the spring 102.

This arrangement is not only efficient in operation but is light in weight and simple in structure so that it can be manufactured rapidly with mass production methods.

While a preferred form of the invention has been illustrated and described, it is to be understood that changes in structure and arrangement may be made without departing from the inventive concepts which are only to be limited to the extent defined in the following claims.

What is claimed is:

1. In a gun mount embodying a standard and a cradle supported by said standard, means for detachably supporting a gun on the cradle so as to permit longitudinal sliding movement of the gun during body recoil thereof, said means comprising a pair of spaced blocks having openings therein and mounted rigidly with the cradle, a pair of parallel rods slidably mounted in the openings in said blocks, means rigid with said rods for detachably supporting said gun, and spring recoil absorbing means disposed between and in contact with said last named means and one of said blocks.

2. In a gun mount embodying a standard and a cradle supported by said standard, means for detachably supporting a gun on the cradle so as to permit longitudinal sliding movement of the gun during body recoil thereof, said means comprising a pair of spaced blocks having openings therein and mounted rigidly with the cradle, a pair of parallel rods slidably mounted in the openings in said blocks, means rigid with said rods for detachably supporting said gun, and spring recoil absorbing means disposed between said last named means and one of said blocks, said recoil means comprising a recoil rod the ends of which pass respectively through said last named means and said last named block, collars fixed on the ends of said recoil rod, and a pair of coil springs on said recoil rod, one of which springs is disposed between and in contact with said last named block and one of said collars, and the other of which springs is disposed between said last named block and said last named means.

3. In a gun mount embodying a standard and a cradle supported by said standard, means for detachably supporting a gun on the cradle so as to permit longitudinal sliding movement of the gun during body recoil thereof, said means comprising a pair of spaced blocks having openings therein and mounted rigidly with the cradle, a pair of parallel rods slidably mounted in the openings in said blocks, means rigid with said rods for detachably supporting said gun, and spring recoil absorbing means disposed between said last named means and one of said blocks, said recoil means comprising a recoil rod the ends of which pass respectively through said last named means and said last named block, collars fixed on the ends of said recoil rod, and a pair of coil springs on said recoil rod, one of which springs is disposed between and in contact with said last named block and one of said collars, the other of which springs being disposed between said last named block and said last named means, said springs having differing tensional properties, the one of lesser tensional strength being positioned to absorb the rebound shock after recoil of the gun.

4. In a gun mount embodying a standard and a cradle supported by said standard, means for detachably supporting a gun on the cradle so as to permit longitudinal sliding movement of the gun during body recoil thereof, said means comprising a pair of spaced blocks rigid with the cradle, a pair of parallel rods slidably mounted in said blocks, means rigid with said rods for detachably supporting said gun, and spring recoil absorbing means disposed between and in contact with said last named means and one of said blocks, said cradle comprising two parallel plates, and said blocks comprising the sole means for supporting the plates in said parallel relationship.
